UNITED STATES PATENT OFFICE.

ALBERT AUG. BIRKHOLOZ, OF ZURICH, SWITZERLAND.

APPARATUS FOR GENERATING ILLUMINATING-GAS.

1,355,530.

Specification of Letters Patent.

Patented Oct. 12, 1920.

Application filed November 10, 1916, Serial No. 130,682. Renewed August 3, 1920. Serial No. 401,080.

To all whom it may concern:

Be it known that I, ALBERT AUG. BIRKHOLOZ, a citizen of the Swiss Republic, residing at Zurich, Switzerland, have invented 5 a certain new and useful Improved Apparatus for Generating Illuminating-Gas, of which the following is a full, clear, and exact description.

The present invention consists of a furnace and process for heating the same for the purpose of generating illuminating gas in vertical retorts or chambers for continuous working.

In the processes hitherto known for periodical or continuous working, the retorts were heated at the broad side either from the top to the bottom or from the bottom to the top.

Certain disadvantages accrue from both 20 systems. With the first mentioned system the fuel coming from the measuring receptacle or bunker immediately into the retort, is at once exposed to the highest temperature, which softens the coal and converts the 25 same into a homogeneous soft mass, which hinders, if it does not entirely prevent, the free escape of the gases developed in the other parts of the retorts. The coal thus converted into a soft homogeneous mass has 30 the further disadvantage that it prevents the regular even fall of the fresh coal, thus endangering the continuous working altogether. In addition to these disadvantages the pipe connections with the retort are 35 liable to get clogged up, which is liable to retard or prevent the proper feed of fuel to the retort and is certain to retard the free escape of the gases developed.

If the retorts are heated from the bottom 40 to the top, there is the drawback that the highest temperature is at the lowest part of the retort, and that this temperature does not by any means decrease evenly and gradually upward, so that a properly regulated 45 heating suitable for the fractionated distillation of the coal, under no circumstances takes place.

According to this invention the retorts are heated from the center or approximately 50 from the center of the furnace, according to the condition necessary for the kind of fuel to be gasified.

Air and gas are combined in a separate mixing chamber and are ignited as they 55 leave the burner nozzles in the furnace. The combustion gases pass first directly over the

broad sides of the upper parts of the retorts from the bottom to the top and pass thence through a flue provided in the furnace wall to the lower retort chamber, through which they pass in a vertical or zig-zag course from top to bottom and are then taken off to the recuperator.

By this method of heating, in contradistinction to the above mentioned systems, the 65 hottest zone is produced in the center of the furnace, which enables the distillation of the fuel to be conducted, so that a preliminary distillation takes place in the upper part of great intensity advancing or increasing 70 downwardly, and after the hottest zone has been passed, a gradually decreasing after-distillation takes place in the lower part of the retort. This is of great importance with continuous working, in order to enable a 75 fractionated distillation and to insure a regular fall of the fresh fuel feed to be distilled.

In the accompanying drawings a furnace is illustrated in which the present process may be carried out.

Figure 1 shows a retort, one half in front elevation and one half in vertical section,

Fig. 2 is a vertical section on the line A—B of Fig. 1.

Fig. 3 is a horizontal section on line 1—1 of Fig. 1.

Fig. 4 a similar section on line 2—2

Fig. 5 a similar section on line 3—3 and

Fig. 6 a similar section on line 4—4 of Fig. 1.

The fuel feed takes place from an intermediate receptacle or measuring drum *a* in communication with the upper end of the retort and hermetically sealed as regards the coal bunker or holder proper. This receptacle *a* is adapted to hold sufficient coal for two or more hours distillation and supplies the same in equal measure to the retort *b* to that in which the coke, from which the gas has been extracted, is taken off from the 90 lower end of the retort.

The retort *c* is divided into two chambers by a horizontal partition wall *d*. In the latter is provided a passage *e* for the preheated air of combustion and also a passage *f* for the heating gases. The former is in communication with a passage *e'* leading from the recuperator, the latter passage being connected by a channel or passage *f'* with the generator. The passages *e* and *f* are connected together by openings, as indicated by arrows and in the said openings, burner noz-

zles *h* are arranged, which may be closed by removable bricks. Communication is established with the upper retort chamber *c* by a passage *g* provided in the furnace wall, 5 which opens into the lower space or chamber *c* close under the partition wall *d*. The lower chamber is provided with a number of horizontal or vertical passages or flues which cause the heating gases to take a zig- 10 zag passage through the lower retort chamber. The lowest passage or flue *k* is in communication with the recuperator and may be closed by movable bricks for regulating the heating. The operation takes place in 15 the following manner:—

The heating gas coming from the generator passes through the channel or flue *f'* into the passage *f* in the partition wall *d* and here mixes with the preheated air of 20 combustion coming from the recuperator and entering the channel *e* in the direction of the arrows. The mixture of air and gas passes through the nozzles *h* where it is ignited. The hot gases pass through the upper 25 retort chamber *c* and pass then through the channel *g* provided in the furnace wall into the lower retort chamber *c*, through which they wind from top to bottom (as indicated by arrows in Fig. 2) in a zig-zag course. 30 The heating gases are led off from the lower retort chamber to the recuperator, through the passage *k*.

In order to effect the proper regulation and heating the generator gas passage *f'*, 35 the nozzles *h*, the heating gas outlets in the upper and lower furnace chambers are provided with adjustable bricks, which may be adjusted through suitable openings provided in the furnace walls.

40 The above described heating process is particularly adapted for uninterrupted or continuous working but it may also be advantageously adapted for periodical working, *i. e.*, for working in alternate periods.

45 I claim as my invention:—

1. A furnace of the class described comprising vertical retorts, a main central horizontal partition extending the entire width of the furnace, thereby dividing it into upper and lower chambers, ignition nozzles in 50 the upper chamber, a series of horizontal partitions extending the entire width of the lower chamber having openings in alternate ends and means for conducting the gas which comes from the ignition nozzles from the upper chamber to the top of the lower chamber from which it passes in a zig-zag course to the bottom thereof and out of the furnace, substantially as described.

60 2. A furnace of the class described comprising vertical retorts, a horizontal partition extending the entire width of the furnace, thereby dividing it into upper and lower chambers, ignition nozzles in the upper chamber, a series of horizontal parti- 65

tions extending the entire width of the lower chamber having openings in alternate ends, a flue in the partition wall through which gas is adapted to pass to the ignition nozzles, and means for conducting the gas which comes from the ignition nozzles from the upper chamber to the lower chamber, where it passes through the horizontal passages and out of the furnace, substantially as described. 75

3. A furnace of the class described comprising vertical retorts, a horizontal partition dividing the furnace into upper and lower chambers, ignition nozzles in the upper chamber, means for admitting gas to the ignition nozzles, means for conducting the gas which comes from the ignition nozzles from the upper chamber to the lower chamber, and out of the furnace and a flue in the partition wall through which air passes, substantially as described. 80

4. A furnace of the class described comprising vertical retorts, a horizontal partition dividing the furnace into upper and lower chambers, ignition nozzles in the upper chamber, flues in the partition wall for the passage of air and gas respectively, means for admitting air from the air flue to the gas flue where the two mix, a passage from the gas flue to the ignition nozzles through which the mixture of air and gas pass, and means for conducting the gas which comes from the ignition nozzles from the upper chamber to the lower chamber and out of the furnace, substantially as described. 95

5. A furnace of the class described comprising vertical retorts, a partition dividing the furnace into upper and lower chambers, ignition nozzles in the upper chamber, flues in the partition wall for the passage of air and gas respectively, means for admitting air and gas to the ignition nozzles, means for conducting the gas which comes from the ignition nozzles from the upper chamber to the lower chamber and out of the furnace, a passage adapted to connect the gas flue with a generator, and a passage adapted to connect the air flue with a recuperator, substantially as described. 105

6. A furnace of the class described comprising vertical retorts, a partition dividing the furnace into upper and lower chambers, ignition nozzles in the upper chamber, a series of horizontal passages in the lower chamber, flues in the partition wall for the passage of air, and gas, respectively, and a passage in the wall of the furnace leading from the top of the upper chamber to the top of the lower chamber for the passage 120 of hot gases coming from the ignition nozzles. 125

7. The method of continuously or periodically generating illuminating gas in vertical retorts which consists in admitting a 130

mixture of air and gas to ignition burners at approximately the center of a furnace, where it is ignited, and causing the hot gases to pass from the center to the top of
5 the furnace and then back to approximately the center and into a chamber where it takes a zig-zag path from top to bottom; thus the upper part of the retort is heated from bot-

tom to the top, and the lower part from the top to the bottom.

In testimony whereof I affix my signature in the presence of two witnesses.
